DOMESTIC APPLIANCE

Donald K. Ferris, Dayton, Ohio, assignor to General Motors Corporation, Dayton, Ohio, a corporation of Delaware

Application August 1, 1942, Serial No. 453,224

9 Claims. (Cl. 38—65)

This invention relates to a domestic appliance and more particularly to an ironing machine.

This application is a continuation-in-part of my copending application Serial No. 318,913, which was filed February 14, 1940 and which is issued as Pat. No. 2,307,833 on Jan. 12, 1943.

At the present time the underwriters' specifications limit the current input of portable domestic ironing machines so that the wattage available for the shoe is limited to about 1300 to 1500 watts. The shoes of these ironing machines vary in area between 100 and 200 square inches. It will thus be seen that this amount of heating capacity per square inch of area is quite small in comparison to a flatiron, most of which are provided with a 1000 watt heating capacity and have an area of about 25 square inches.

This lower heat density results in slower temperature recovery of the shoe and in the past it has been necessary to limit the size of the ironing machine shoe or to limit the maximum speed of the roll or both. It is quite obvious that if only a small heating capacity is available that the ironing machine must be run comparatively slow so that any material being pressed on the ironing machine will be heated sufficiently to be properly ironed.

This limitation of heat recovery is especially noticeable where ironing is done continuously under one portion of the shoe of the ironing machine.

It is an object of my invention to provide an improved heating circuit arrangement for the shoes of ironing machines which will make a more advantageous disposition of the wattage to heat the shoes available to permit the use of either a larger size ironer shoe or greater roll speed in ironing or both.

It is another object of my invention to provide an improved heating circuit arrangement for the shoes of ironing machines for the purpose of concentrating the heating capacity at the point or portion at which it is needed when it is needed.

It is another object of my invention to provide an improved circuit arrangement for the shoe of an ironing machine whereby a much greater proportion of heat may be supplied to one end, preferably the open end of the ironing machine when needed at this point and to provide a suitable thermostatic control for such an arrangement.

It is still another object of my invention to provide an ironing machine having a plurality of shoes with a plurality of heating circuits each

of the maximum 1300 watt capacity controlled in such a way that they are used alternatively to provide a greater heating capacity in the ironing shoe being used and therefore requiring the most heat.

Further objects and advantages of the present invention will be apparent from the following description, reference being had to the accompanying drawings wherein a preferred form of the present invention is clearly shown.

In the drawings:

Fig. 1 is a top view of an ironing machine embodying my invention;

Fig. 2 is a wiring diagram for a two-shoe type of ironing machine embodying one form of my invention;

Fig. 3 is a vertical sectional view taken on line 3—3 of Fig. 1;

Fig. 4 is a simplified two-circuit arrangement for a two-shoe ironing machine.

Figs. 5, 6 and 7 are simplified showings of the same circuit shown in Fig. 2 and are intended to more clearly illustrate a few of the possible circuit arrangements by showing the energized circuits in heavy lines. These figures also show the main power switch and the means for adjusting the thermostat in the big shoe; and

Fig. 8 shows a chart which indicates the wattage available for heating the big shoe and the little shoe for various settings of the manual control 94 and the thermostats 84 and 124 shown in Figs. 2, 5, 6 and 7.

Referring now to the drawings, there is shown an ironing machine of the two-shoe type includ-

35 ing a large shoe 60 and a small shoe 62. These shoes are both made so that either or both can be released at any time. This is illustrated in Fig. 3 in which the small shoe 62 is shown as being pressed against the roll 64. The releasing

40 of the small shoe 62 is controlled by the lever 66 while the releasing of the large shoe is controlled by the lever 68. The releasing mechanism for each of these shoes is substantially identical and the releasing mechanism for the

45 large shoe 60 is clearly shown in this figure. The releasing lever 68 is pivoted upon the pivot pin 70 to a hollow arm 72 which is rotatably mounted upon the hollow rod 74. The large shoe 60 is likewise pivotally connected by the pin 70 to the arm 72. A stiff spring of the cantilever type 76 has its lower end anchored in the rod 74 and extends within the arm 72. A light spring 78 is also provided for engaging the inner wall of the arm 72. The releasing lever 68 is provided with 50 an extension 80 within the arm 72 which is adapt-

ed to engage the upper end of the spring 76. When the releasing lever 68 is pulled downwardly the end 76 presses against the end of the spring 76 to move the arm 72 and the shoe 60 in a counter-clockwise direction to press the shoe 60 onto the roll 64. In order to release the shoe 60, the release lever 68 is moved to the position shown in the figure so that the spring 76 will no longer hold the shoe 60 against the roll.

In Fig. 2 I have shown a wiring diagram providing a plurality of circuit arrangements for obtaining better heating of such an ironing machine. Figs. 5, 6 and 7 have been prepared to more clearly show this same circuit arrangement without regard to the exact physical arrangement of the various elements. In the small shoe, I provide a heating element 82 which may extend around the edges of the shoe and preferably has a capacity of about 175 watts when connected in series with the heating element 110 but has a capacity of about 700 watts when connected directly across the supply conductors. The energization of this heating element 82 is controlled by a double acting thermostat 84 which is connected by the conductor 86 to source conductor 88. When the shoe is cool, the thermostat 84 will make engagement with the contact 90 to connect the heating element 82 to the source 88. The other end of the heating element is connected by a conductor 92 to a manual switch 94 having two sets of switch contacts, one designated by the reference character 96 and the other by the reference character 98. This switch 94 is operated by the release lever 68 as shown in Fig. 3.

This switch 94 has an operating pin 102 which is adapted to be held in engagement with the adjacent portion of the release lever 68 by a suitable spring. When the large shoe is in operating position, the switch 94 will assume the position shown in Figs. 2, 5, 6 and 7 whereby the lower contacts 98 will be closed and the upper contact 96 will be in the open position. The contacts 98 connect the conductor 92 to a conductor 104. This conductor 104 is connected to the upper thermostat contacts 108. These contacts 108 control the connection of conductor 104 with a small heating element 110 in the large shoe 60. This small heating element preferably has a heating capacity of 175 watts when connected in series with the heating element 82, as shown in Fig. 6, and about 700 watts when connected directly across the supply conductors, as shown in Fig. 7. This heating element 110 is connected to the other supply conductor 114, as shown in Fig. 2 for example.

The thermostat 84 is provided with a second contact 116 which connects to a conductor 118 for the purpose of short-circuiting the heating element 82 and the switch 94 when the small shoe 62 is heated sufficiently and does not require any heat at that time. This will allow full voltage to be impressed upon the heating element 110 so that it will then supply 700 watts, as shown in Fig. 7. However, should the large shoe be released by moving its release lever 68 to the position shown in Fig. 3, the switch 94 will be operated to open the contacts 98 and to close the contacts 96 so that the heating element 82, subject only to the control of the thermostat 84, will be connected directly across the conductors 88 and 114 in a circuit which includes the conductor 86, the contact 90, the heating element 82, the conductor 92, the switch contacts 96 and the

conductor 120. This will double the heating capacity of the heating element 82 and supply the small shoe with a heating capacity of 700 watts. This condition is set forth as condition number 1 on the chart shown in Fig. 8. This chart shows the distribution of the heat for various other control settings also.

The large shoe 60 is also provided with a main heating element 122 of 600 watts. This main heating element is positioned at the front of the shoe 60 and is connected directly across the supply conductors 88 and 114 under the control of the large shoe thermostat 124 and contacts 126. A conductor 128 connects the contacts 126 with the supply conductor 88 while the other end of the heating element 122 is connected to the supply conductor 114. The thermostat 124 also controls the contact 108 so that it controls the energization of both the heating elements 110 and 122. In Fig. 5, I have shown a sectional view of a means for adjusting the setting of the thermostat 124 so as to control the temperature at which the thermostat 124 moves the contacts 108 and 126 to the closed circuit position. The thermostat shown is intended to designate any conventional thermostat used for regulating the temperature. Reference numeral 200 designates a cam which, when rotated by the knob 201, adjusts the setting of the thermostat. A spring 202 wedges the thermostat against the cam 200. Thermostats of this general type are well known and may be set to deliver maximum heat, no heat whatsoever, or any intermediate amount of heat. The cam 200 and the spring 202 are mounted in a suitable casing 203.

When the thermostat 124 is in its open circuit position, as shown in Fig. 5, the contact 108 will connect the conductor 104 with a conductor 111 which shunts the heating element 110. This makes it possible for the thermostat 84 to connect the element 82 across the supply conductors 88 and 114, as shown in Fig. 5, so as to impress the full voltage upon the element 82 to give it a heat output of 700 watts whenever the thermostat 124 is in the open position instead of the 175 watt capacity available when the thermostat 124 is in the closed position, as shown in Fig. 6. When the thermostat 124 is in the closed position, the contact 108 connects the element 110 to the conductor 104.

Thus by this circuit arrangement, when only the small shoe is being used, it is provided with a heating capacity of 700 watts while the idle large shoe is provided with 600 watts to maintain it in a heated condition. When both shoes are being used and the thermostat 124 calls for heating, the small shoe is provided with a heating capacity of 175 watts and the large shoe with the heating capacity of 775 watts. When the small shoe requires no heat, the large shoe is provided with a heating capacity of 1300 watts, as shown in Fig. 7. Although I have specified different wattages for the different heating elements, it should be understood that these different wattages can be proportioned as desired in order to obtain the desired heat distribution within the maximum permissible limit. Thus by providing a plurality of heating circuits of the maximum available heating capacity of 1300 watts each, I can concentrate the heating capacity wherever it is needed or wherever it is desired whenever it is desired. A conventional master control switch 204 is shown in the line 114 in Figs. 5, 6 and 7 for turning off all of the heating elements in accordance with standard practice.

In Fig. 4, there is shown a simplified wiring diagram for the two-shoe arrangement shown in Fig. 2. In this figure the small and large shoes are designated by the reference characters 262 and 260. The large heating unit in the large shoe is designated by the reference character 222 while the small heating element is designated by the reference character 210. The heating element in the small shoe is designated by the reference character 282. In this simplified form, the main heating element 222 is connected across the supply conductors 288 and 214 under the control of the thermostat 224. The small element 210 and the element 282 of the small shoe are connected in series with the small shoe thermostat 284 across the supply conductors 288 and 214.

A shunt including the conductors 204 and 220 as well as the switch 294 is provided for the small heat element 210 in the large shoe. The switch 294 is a diagrammatic form of the switch 94, as shown in Fig. 3, and is intended to be operated in the same manner so as to close the shunt for the small heating element of the large shoe whenever the large shoe is released, as shown in Fig. 3. This shunting of the small heating element 210 thus connects the small shoe heating element 282 and the small shoe thermostat 284 directly across the supply conductors 288 and 214, thereby increasing the voltage applied to the heating element 282 and greatly increasing the wattage.

The heating elements may be proportioned as suggested in connection with Fig. 2 or they may be varied as desired. Thus in this form the switches and circuits are less complicated and yet means is provided for increasing the heat output of the small shoe 262 whenever the large shoe is released. This wiring circuit is intended to be used with an ironing machine such as is shown in Fig. 3.

While the form of embodiment of the invention as herein disclosed constitutes a preferred form, it is to be understood that other forms might be adopted, all coming within the scope of the claims which follow.

What is claimed is as follows:

1. An ironing machine comprising a movable ironing member, a first shoe and a second shoe to cooperate with said ironing member, control means for disconnecting one of said shoes from cooperation with said ironing member, a first heating means in said first shoe, a second heating means in said second shoe, and means operated by said control means deenergizing one of said heating means without deenergizing the other of said heating means when said control means disconnects one of said shoes.

2. An ironing machine comprising a movable ironing member, a first shoe and a second shoe to cooperate with said ironing member, control means for disconnecting one of said shoes from cooperation with said ironing member, a first heating means in said first shoe, a second heating means in said second shoe, a first thermostat controlling energization of said first heating means, a second thermostat controlling energization of said second heating means, and means operated by said control means deenergizing one of said heating means without deenergizing the other of said heating means when said control means disconnects one of said shoes.

3. An ironing machine including an open end roll and an open end shoe means, a first heating means concentrated at the open end portion of said shoe means, a second heating means concentrated in another portion of said shoe means

away from said open end, thermostatic control means preferentially connecting said heating means to concentrate more heat at said open end portion irrespective of the temperature at the closed end as long as required.

4. An ironing machine including an open end roll and an open end shoe means, a first heating means concentrated at the open end portion of said shoe means, a second heating means concentrated in another portion of said shoe means away from said open end, thermostatic control means preferentially connecting said heating means to concentrate more heat at said open end portion irrespective of the temperature at the closed end as long as required and thereafter to concentrate more heat in said another portion of said shoe means away from said open end.

5. An ironing machine comprising in combination, a roll, shoe means cooperating with said roll, a first resistance heating means concentrated in a first portion of the shoe means, second and third resistance heating means concentrated in a second portion of the shoe means, a pair of electrical supply lines for supplying electricity to said resistance heating means, means for connecting said first and second resistance heating means in series across said supply lines, means for connecting said third resistance element directly across said supply lines in parallel with said first and second resistance elements, and means for short circuiting said second heating means whereby said first heating means is connected directly across said lines.

6. An ironing machine comprising in combination, a roll, shoe means cooperating with said roll, a first resistance heating means concentrated in a first portion of the shoe means, second and third resistance heating means concentrated in a second portion of the shoe means, a pair of electrical supply lines for supplying electricity to said resistance heating means, means for connecting said first and second resistance heating means in series across said supply lines, means for connecting said third resistance element directly across said supply lines in parallel with said first and second resistance elements, means for short circuiting said second heating means whereby said first heating means is connected directly across said lines, said first and second portions of said shoe means each being independently movable into and out of ironing engagement with said roll, and said means for short circuiting said second heating means being operable to short circuit said second heating means whenever said second portion of said shoe means is moved out of ironing engagement with said roll.

7. An ironing machine comprising a movable ironing member, a first shoe and a second shoe to cooperate with said ironing member, control means for disconnecting one of said shoes from cooperation with said ironing member, a first resistance heating means in said first shoe, a second resistance heating means in said second shoe, means connecting said first and second heating means in series, and means operated by said control means deenergizing one of said heating means without deenergizing the other of said heating means when said control means disconnects one of said shoes.

8. In an ironing machine including a roll and shoe means cooperating with said roll, a plurality of resistance heating means in said shoe means, a pair of electrical supply lines for supplying electricity to said resistance heating means, means for connecting a pair of said resistance

heating means in series across said supply lines, said pair of heating means being located in different parts of said shoe means and being of substantially equal electrical resistance, means for connecting a third resistance element directly across said supply lines in parallel with said first and second resistance elements, said third resistance element being located in one of said parts of said shoe means and being of substantially greater electrical resistance than either of said pair of heating means but having greater heating capacity than said pair of heating means when connected in series, and means for altering the distribution of heat in said shoe means including means for short-circuiting one of said pair of resistance heating means.

9. An ironing device comprising in combination, pressing means, a first resistance heating means concentrated in a first portion of the pressing means, second and third resistance heating means concentrated in a second portion of the pressing means, a pair of electrical supply lines for supplying electricity to said resistance heating means, means for connecting said first and second resistance heating means in series across said supply lines, means for connecting said third resistance element directly across said supply lines in parallel with said first and second resistance elements, and means for short circuiting said second heating means whereby said first heating means is connected directly across said lines.

DONALD K. FERRIS.
